CIGARETTE CASE

Georg Reitzel, Gelnhausen, Germany, assignor to Drescher & Kiefer, Gelnhausen, Germany, and Randolph-Rand Corporation, New York, N.Y., fractional part interest to each

Filed Nov. 4, 1969, Ser. No. 19,926

Term of patent 14 years

Int. Cl. D27—06

U.S. Cl. D85—2

FIG. 3

FIG. 1

FIG. 4

FIG. 5

FIG. 6

FIG. 2

FIG. 7

FIG. 1 is a front elevational view of a cigarette case showing my new design;

FIG. 2 is a rear elevational view;

FIG. 3 is an elevational view looking from the left of FIG. 1;

FIG. 4 is an elevational view looking from the right of FIG. 1;

FIG. 5 is a top plan view;

FIG. 6 is a bottom plan view; and

FIG. 7 is a front elevational view with the top of the cigarette case in open position.

The characteristic features of my design reside in the configuration and appearance of the lid portion of the cigarette case.

I claim:

The ornamental design for a cigarette case, as shown and described.
